UNITED STATES PATENT OFFICE.

WILLIAM B. TUNSTALL, OF WORCESTER, MASSACHUSETTS.

REGISTERING MECHANISM FOR THE TRACKER-BOARDS OF MUSICAL INSTRUMENTS.

No. 841,740.

Specification of Letters Patent.

Patented Jan. 22, 1907.

Application filed March 9, 1905. Serial No. 249,157.

To all whom it may concern:

Be it known that I, WILLIAM B. TUNSTALL, a citizen of the United States, residing at Worcester, in the county of Worcester and State of Massachusetts, have invented a new and useful Registering Mechanism for the Tracker-Boards of Musical Instruments, of which the following is a specification.

This invention relates to that class of mechanisms which are controlled by strips of perforated paper.

The especial object of this invention is to provide pneumatically-operated means for maintaining registration between the perforated strip and its tracker-board.

To these ends this invention consists of the parts and combinations of parts as hereinafter described, and more particularly pointed out in the claims at the end of this specification.

In the accompanying drawings, Figure 1 is a front view of sufficient parts of the winding mechanism for a perforated strip to illustrate the application of my invention thereto. Fig. 2 is an inverted perspective view of one of the dovetailed pieces containing one of the adjustable margin perforations which control connections for automatically maintaining registration, and Fig. 3 is a fragmentary longitudinal sectional view through the center of the end of the tracker-board.

In the use of automatic musical instruments and other mechanisms of the class to which this invention relates a great obstacle to be overcome in securing accurate and perfect effects is the difficulty of maintaining the perforated strip in exactly the desired relation to the tracker-board. Many of the instruments of the class to which this invention relates are provided with tracker-boards having exceedingly small holes. The paper itself is frequently required to be of a considerable width, and it has been found in practice that variations in humidity of the atmosphere and changes in temperature will cause the paper to shrink or swell to such extents that the perforations are apt to be thrown out of alinement with the tracker-board holes, so that only imperfect and unreliable effects can be produced. To overcome this, it has been proposed to employ music-spoils having spring-pressed flanges and to employ various guiding devices for insuring the accurate winding of the paper; but even when the utmost care is exercised it

has frequently been found to be impossible to prevent the paper from "wandering" so as to bring its perforations out of alinement with the tracker-board holes. To overcome this difficulty, in an apparatus constructed according to my invention I provide a pneumatically-operated registering mechanism which will produce a relative movement of the parts to automatically maintain the paper in registration with its tracker-board.

In carrying out my invention I preferably employ marginal perforations in the tracker-board which are adjustable toward and from each other. These marginal perforations are intended to lie immediately below the outer edges of the perforated sheet, and in order to adjust the mechanism to variations in width of paper, due to swelling by reasons of variations in moisture or other causes the marginal perforations are preferably made adjustable toward and away from each other, being set closer together when narrow paper is being used and being spread farther apart when somewhat wider paper is being used.

Controlled from the marginal perforations are two opposing sets of pneumatic-operating connections, one set of operating connections being permitted to act when one marginal perforation is uncovered and the other set of operating connections being permitted to act when the other marginal perforation is uncovered.

The pneumatic connections when operated produce a relative adjustment between the tracker-board and the paper.

In the construction herein illustrated the supply-spool is the part which is shifted to correct registration. It is obvious, however, that the same result might be secured by shifting the tracker-board, if desired.

Referring to the accompanying drawings for a detail description of an apparatus embodying this invention, F designates the supporting-frame of an instrument of the class to which this invention relates. Rotatably mounted in the frame F are the elongated journals 21 and 22 for the supply-spool R. From the spool R the perforated strip of paper S is drawn over the tracker-board T and wound upon the winding-roll W. The winding-roll W is provided at its end with a gear.

The longitudinally-movable driving-shaft P is provided at its end with a pinion normally meshing with the gear of the winding-roll. Loosely mounted upon the shaft I is a

driving sprocket-wheel C, which is held from transverse movement, and cooperating with the sprocket-wheel C is a clutch-piece E.

When the driving-shaft P is shifted from the position shown, the pinion D will be drawn out of mesh, and the driving sprocket-wheel C will be operated, so that its driving-chain will turn the sprocket-wheel H upon the journal 22 of the supply-spool, so as to 10 wind the perforated strip thereon. A friction brake I is employed for maintaining the tension of the paper during winding.

The parts as thus far described may be of substantially the ordinary or usual construction.

Referring now to the means for maintaining the registration of the perforated strip S, with its tracker-board T, I provide near the opposite ends of the tracker-board dove-tailed movable pieces 10 and 11, which movable pieces are provided with perforations which normally lie immediately below the outer margins of the perforated strip S. Connected with the movable piece 10 is a hand-lever 12, and connected with the movable piece 11 is a lever 13. The levers 12 and 13 are connected by a rod 14, and it is to be observed that the levers are pivoted on relatively opposite sides of the movable pieces 15 10 and 11, so that when the hand-lever 12 is pushed in one direction the marginal perforations will be brought closer together to cooperate with the narrow strip of perforated paper and when the hand-lever 12 is pushed in the opposite direction the marginal perforations will be separated to cooperate with a wider strip of perforated paper.

Controlled from the marginal perforations are two sets of pneumatic operating means, 40 which sets of mechanisms are of similar construction, so that a description of but one of such sets is required.

Leading from each of the marginal perforations is a pipe 15, which connects to a primary pneumatic 16. Controlled from the primary pneumatic 16 are the valves 18 and 19. A suction-pipe connected with any of the ordinary exhaust-bellows or other source of air-tension is connected above the exhaust-chest above primary pneumatic 16, and when the valves are in the normal position illustrated suction is maintained in the operating pneumatic 20.

The operating pneumatics 20 at opposite sides of the apparatus engage the journals 21 and 22 of the music-roll, respectively, and in order to assist the action of the pneumatics I employ spring connections normally tending to draw in said pneumatics. As herein illustrated, these connections comprise the rod 23 and the springs 24. By means of this construction, whenever either one of the marginal perforations is uncovered by reason of the wandering or lack of registration of the 65 perforated strip, atmospheric pressure will

be admitted to the operating pneumatic at the same side of the apparatus as the marginal perforations which is uncovered, so that the suctional force upon the operating-pneumatic at the other side of the apparatus will be unbalanced, and the roll will be shifted back, so that the sheet will be instantly brought to registered position.

I am aware that numerous changes may be made in practicing this invention by those who are skilled in the art, and while I have illustrated my invention applied to an apparatus in which registration is secured by shifting the supply-roll other connections may be employed for securing the desired relative shifting movement of the parts, and although my invention is especially applicable to automatic musical instruments it may be applied to advantage to any class of mechanisms which are controlled by perforated strips of paper.

I am aware that many changes may be made by skilled mechanics in practicing my invention without departing from the scope thereof as expressed in the claims. I do not 90 wish, therefore, to be limited to the construction I have herein shown and described; but

What I do claim, and desire to secure by Letters Patent of the United States, is—

1. The combination of a tracker-board, 95 means for maintaining registration between a perforated strip and the tracker-board, said tracker-board having movable means located near each end for controlling the first-named means, and means for simultaneously moving the controlling means toward or from the center of the tracker-board.

2. The combination of a tracker-board having near each end a movable piece provided with a perforation, means for maintaining registration between a perforated strip and the tracker-board controlled by said perforations, and means for simultaneously moving both perforated pieces either inwardly or outwardly along the tracker-board.

3. In a construction of the class described, the combination of the winding-rolls for a perforated strip, a tracker-board having pieces provided with marginal perforations, means for simultaneously adjusting the pieces having said marginal perforations to cooperate with strips of different widths, and pneumatically-operating means controlled from said marginal perforations for maintaining registration between the perforated strip and tracker-board.

4. In a construction of the class described, the combination of winding-rolls for a perforated strip, a tracker-board having marginal perforations, and two sets of relatively, oppositely acting pneumatic operating means, one of which tends constantly to shift the perforated strip in one direction, and the other of which tends constantly to shift the

music-sheet in the opposite direction while the instrument is in operation, said means being controlled by the marginal perforations.

5. In an apparatus of the class described, the combination of winding-rolls for a perforated strip, a tracker-board, a piece movably mounted near each end of the tracker-board and having a marginal perforation therein, a hand-lever and connections for moving said 10 marginal perforations toward each other to coöperate with narrow strips, and for separating the marginal perforations to coöperate with wider strips, and two sets of relatively, oppositely acting, pneumatic connections 15 controlled from said marginal perforations, each set comprising a primary pneumatic, an operating-pneumatic, valves controlled by the primary pneumatic for normally connecting the operating-pneumatic with the exhaust, and springs normally assisting the operation of the pneumatics, whereby whenever one of the longitudinal perforations is uncovered, the operating 20 connections at the other side of the apparatus will act to shift the perforated strip back to registered position.

6. In an apparatus of the class described, the combination of winding-rolls for a perforated strip, a tracker-board, a piece movably 30 mounted near each end of the tracker-board and having a marginal perforation therein, a lever, and connections for simultaneously moving both of said pieces having marginal perforations toward each other to coöperate 35 with narrow strips and for separating the marginal perforations to coöperate with wider strips.

7. In an apparatus of the class described, the combination of winding-rolls for a perforated strip, a tracker-board having adjustable 40 pieces provided with marginal perforations, and two sets of relatively oppositely acting pneumatic connections controlled from said marginal perforations, each set comprising a

primary pneumatic, an operating-pneumatic, 45 valves controlled by the primary pneumatic for normally connecting the operating-pneumatic with the exhaust, and springs normally assisting the operation of the pneumatics, whereby whenever one of the longitudinal perforations is uncovered, the operating 50 connections at the other side of the apparatus act to shift the perforated strip back to registering position.

8. In an apparatus of the class described, 55 the combination of a pair of winding-rolls for a perforated strip, a reciprocable support having bearings for one of said winding-rolls, a tracker-board having marginal perforations, and two pneumatics, one connected with each end of the reciprocable support, said pneumatics being normally under tension when said perforations are closed and tending to force the reciprocable support in opposite directions, said pneumatics being controlled from said marginal perforations.

9. In an apparatus of the class described, the combination of a pair of winding-rolls for a perforated strip, a reciprocable support having bearings for one of said winding-rolls, 70 a tracker-board having marginal perforations, two pneumatics, one connected with each end of the reciprocable support, said pneumatics being under tension when said perforations are closed and tending to force the reciprocable support in opposite directions, 75 said pneumatics being controlled from said marginal perforations, and resilient means for assisting in the operation of the pneumatics.

In testimony whereof I have hereunto set my hand in the presence of two subscribing witnesses.

WILLIAM B. TUNSTALL.
